Patented Dec. 27, 1966

206,542

TOY GUN

John W. Ryan, Bel Air, and Floyd Evan Schlau, Redondo Beach, Calif., assignors to Mattel, Inc., a corporation of California

Filed Jan. 20, 1966, Ser. No. 696

Term of patent 14 years

(Cl. D34—15)

We claim:

The ornamental design for a toy gun, as shown.
